DESIGN FOR A CHAIR

Albert J. Berna, Royal Oak, Mich.

Application August 25, 1938, Serial No. 79,568

Term of patent 3½ years

To all whom it may concern:

Be it known that I, Albert J. Berna, a citizen of the United States, residing at 26088 Brettonwood, Royal Oak, in the county of Oakland and State of Michigan, have invented a new, original, and ornamental Design for a Chair, of which the following is a specification, reference being made to the accompanying drawing, forming part thereof.

The drawing is a perspective view of a chair embodying my new design.

I claim:

The ornamental design for a chair, substantially as shown.

ALBERT J. BERNA.
